UNITED STATES PATENT OFFICE

JAMES HOWARD YOUNG, OF PITTSBURGH, PENNSYLVANIA, ASSIGNOR TO H. H. ROBERTSON COMPANY, OF PITTSBURGH, PENNSYLVANIA, A CORPORATION OF PENNSYLVANIA

TIE MEMBER FOR PROTECTED METAL SHEETS

Application filed May 31, 1930. Serial No. 458,833.

This invention relates to a strap or tie-member for attaching metal sheets, which form the roof or side walls of buildings or like structures, to the roof and wall supporting members of the buildings.

The improved tie member is especially adapted for use in buildings whose roofs and side walls are formed by metal sheets provided with asphalt or like bituminous material for protecting the metal sheets against the weather and acid and alkali fumes.

Protected metal sheets of the character described are largely employed in buildings having a framework of steel, and prior to the present invention these sheets have been fastened to the steel framework by straps or tie-members composed of galvanized iron or steel strips, which are of limited life as compared with the asphalt-protected metal sheets, but which heretofore have been the most available devices for the purpose.

The present invention has for its object to provide an asphalt-protected steel or iron tie-member or strap, whose life is substantially the same as that of the protected metal sheets and which can be commercially and economically manufactured, and have its ends bent and provided with holes for the passage of bolts, rivets or like fastening devices, and in which the bent ends of the metal member of the strap are protected by a coating made of asphalt or like bituminous material, which seals the ends of said metal member and the walls of the holes in the bent end portions, and which is united with and reinforces the exterior protective coating on said strap or tie-member.

The improved protected strap or tie-member may and preferably will be produced in a novel manner as will be hereinafter described.

The particular features of the invention will be pointed out in the claims at the end of this specification.

Fig. 1 represents a portion of the roof of a

building provided with protective metal sheets secured to a purlin by means of a tie member embodying this invention;

Fig. 2, a section on the line 2—2, Fig. 1;

Fig. 3, a portion of a side wall having its protected metal sheets secured to the metal frame by the improved tie member;

Fig. 4, a side elevation of a protected metal strip of substantial length from which a plurality of the improved straps or tie-members are produced;

Fig. 5, a longitudinal section of a portion of the protected metal strip shown in Fig. 4, to illustrate the preferred construction of the said strip;

Fig. 6, a side elevation of a strap blank cut out of the strip shown in Fig. 4 and provided with bent ends having holes punched therethrough;

Fig. 7, an elevation like Fig. 6 showing the bent ends covered by the end-sealing members to form the completed strap or tie member, illustrated in Figs. 1 to 3;

Fig. 8, a plan view of the strap shown in Fig. 7;

Fig. 9, an enlarged cross section on the line 9—9, Fig. 8, and

Fig. 10, an enlarged longitudinal section on the line 10, Fig. 8, showing the end sealing member as completely filling the hole in the end of the strap.

Referring to Figs. 1 to 2, 10 represents an asphalt-protected metal sheet which is tied to a purlin or roof-supporting member 12 of a building or like structure by a strap or tie-member 13 embodying this invention.

The tie-member or strap 13 is shown in detail in Figs. 5 to 10 inclusive and comprises essentially a relatively narrow and thin flexible metal member or core 14, a seamless, tubular member 15, preferably a braided tube of textile material, which is saturated with asphalt or like bituminous material 16, preferably a relatively high-melting point but soft asphalt, and enveloped by a flexible cov-

ering or coating 17 of substantial thickness and preferably of the stearin pitch type comprising a relatively high-melting point asphalt containing stearin pitch.

5 The strap or tie-member 13 is also provided with bent ends or flanges 18 having holes 19 for the passage of bolts or other fastening devices 20, and said flanges are provided with a protective coating or sealing member 21 of asphalt or like bituminous material, 10 which covers the top, bottom, and side surfaces of the flanges and also the ends thereof and more or less fills the holes in said flanges. The sealing member 21 is united 15 with the protective coating 17.

15 The strap or tie-member 13 may be commercially and economically made as will now be described.

20 A relatively long or continuous length of metal strip substantially oblong in cross-section and plain or uncoated or as may be preferred, provided with a coating 23 of asphalt is fed through a braiding machine, not shown, but of suitable size to enable the metal strip 25 14 to be passed through the machine and have braided thereon the fibrous tubular member 15 which is substantially oblong in cross section.

25 The metal strip 14 covered by the fibrous tubular member 15 is then wound into the 30 form of a coil and subjected to the action of a bath of asphalt, preferably maintained at or about a temperature of 300° F. until the fibrous tubular member 15 is saturated with the asphalt, which also passes through the 35 interstices of the tubular fibrous member and covers the metal core 14 if a plain core is used, or unites with the asphalt coating on the metal strip or core 14, if the latter is coated 40 with asphalt before being run through the braiding machine. The coil is then allowed to cool and is then run through coating rolls, not shown, which apply the protective coating 17 to the asphalt-saturated tubular fibrous 45 member.

45 The protective coating 17 may and preferably will be of stearin pitch type.

50 The continuous strip produced in this manner is of material length and is represented 55 in Fig. 4 and is of such length as to enable it to be cut up into suitable lengths to form strap blanks 30, represented by the sections or lengths between the lines 31 in Fig. 4, and a portion of which strap blank is represented 55 in section in Fig. 5.

55 The strap blanks 30 of the coated strip illustrated in Fig. 4, intermediate the endmost blanks have both ends of the metal core 14 and of the tubular fibrous member exposed, 60 after the manner represented in Fig. 5.

60 The strap blanks 30 are then bent at their ends to provide the blanks with the end flanges 18 which are punched to form holes 65 19 for the passage of the bolts 20 or like fastening devices.

A strap blank 30 provided with the end flanges 18 having the holes 19 is illustrated in Fig. 6, and such strap blank has the ends of its metal core 14 and the walls of the holes 19 in said core exposed to the corrosive action of the weather and acid and alkali fumes, which would be objectionable, and these exposed ends are then sealed and protected by the sealing members 21 of asphalt, which may be effected by dipping the ends of the strap blank into heated or melted asphalt or like bituminous material.

70 The sealing asphalt members 21 may partially fill the holes 19 in the strap blank after the manner represented in Fig. 9, or they 75 may completely fill the holes as represented in Fig. 10, thereby providing a member of asphalt which co-operates with the bolt 20 passed through the hole and serves to prevent moisture passing along the bolt and 80 gaining access to the metal core of the corrugated protected metal sheets 10.

85 The end-sealing member 21 of asphalt overlaps and unites with the protective coating 90 16 and is thus firmly retained in place and reinforces the said coating at the ends of the 95 strap or tie-member.

100 In Figs. 7 to 10 inclusive the end-sealing member 21 is illustrated on an enlarged scale 95 so as to enable it to be clearly shown and its 105 function understood.

110 It will be observed that by the process herein described, the straps or tie-members may be commercially produced at a minimum 100 cost.

115 What is claimed is:

1. A tie-member of the character described, comprising a tie-member blank having a flexible corrodible metal core whose ends are normally exposed, a flexible tubular fibrous member enveloping said metal core, a flexible weather-resisting bituminous protective coating covering the tubular fibrous member and leaving the ends of said metal core uncovered, and a bituminous sealing member covering the normally exposed ends of said metal core and overlapping and 120 united with said bituminous protective coating.

2. A tie-member of the character described, comprising a tie-member blank having a flexible corrodible metal core whose ends are normally exposed, a flexible tubular fibrous member enveloping said metal core, a flexible weather-resisting bituminous protective coating covering the tubular fibrous member and leaving the ends of said metal core uncovered, said blank having at its ends flanges provided with holes extended through 125 said protective coating, tubular fibrous member and said metal core, and a bituminous sealing member covering the normally exposed ends of the said metal core and extended into the holes therein and overlapp- 130

ping and united with the protective coating beyond said holes.

3. A tie member of the character described, comprising a tie-member blank of ⁵ corrodible metal substantially rectangular in cross section and having normally exposed ends, a flexible braided fibrous member enveloping said metal core and substantially rectangular in cross section, an asphalt coating ¹⁰ saturating said braided fibrous member and covering said corrodible metal blank, a flexible protective bituminous coating of substantial thickness covering said asphalt coating, and a bituminous sealing member ¹⁵ covering the normally exposed ends of said metal core and overlapping and united with said protective coating.

In testimony whereof, I have signed my name to this specification.
